UNITED STATES PATENT OFFICE.

FREDERICK E. GREENE, OF MOUNT VERNON, NEW YORK, ASSIGNOR TO MOUNT VERNON COMPANY SILVERSMITHS INCORPORATED, OF MOUNT VERNON, NEW YORK, A CORPORATION OF NEW YORK.

DESIGN FOR A SPOON, FORK, OR SIMILAR ARTICLE.

49,058.

Specification for Design.

Patented May 16, 1916.

Application filed August 9, 1915. Serial No. 44,658. Term of patent 3½ years.

To all whom it may concern:

Be it known that I, FREDERICK E. GREENE, a citizen of the United States, residing at Mount Vernon, in the county of Westchester and State of New York, have invented a new, original, and ornamental Design for Spoons, Forks, or Similar Articles, of which the following is a specification, reference being had to the accompanying drawing, forming a part thereof, in which—

Figure 1 is a plan view of the utensil; Fig. 2 is a cross sectional view on line 2—2

of Fig. 1; Fig. 3 is a cross sectional view on line 3—3 of Fig. 1 showing my new design.

I claim:

The ornamental design for a spoon, fork, or similar article, as shown.

Signed by me at Mount Vernon, New York, this 4th day of August, 1915.

FREDERICK E. GREENE.

Witnesses:

FRANK H. WELLS,
Jos. T. BROWN.
